UNITED STATES PATENT OFFICE.

FRANK A. GILCREST, OF PASADENA, CALIFORNIA.

INSULATING FABRIC.

1,371,755.

Specification of Letters Patent. Patented Mar. 15, 1921.

Application filed July 25, 1919. Serial No. 313,243.

To all whom it may concern:

Be it known that I, FRANK A. GILCREST, a citizen of the United States, residing at Pasadena, in the county of Los Angeles and 5 State of California, have invented certain new and useful Improvements in Insulating Fabrics; and I do hereby declare the following to be a full, clear, and exact description of the invention, such as will enable others 10 skilled in the art to which it appertains to make and use the same.

The present invention relates to insulating fabric more particularly adapted for use in the construction of wearing apparel, 15 blankets, automobile hood covers, and the like.

The object is to provide a fabric embodying a structure for retaining a quantity of infusorial earth or similar substance in flat, 20 spread condition throughout the extent of the fabric to impart the desired insulating qualities to the fabric against the passage of heat, vibration and the like.

With these and further objects in view 25 as will in part hereinafter become apparent and in part be stated, the invention comprises certain novel constructions, combinations and arrangements of parts as subsequently specified and claimed.

30 In the accompanying drawing,—

Figure 1 is a diagrammatic plan view of a portion of fabric constructed according to the present invention.

Fig. 2 is a detail edge view of a strip 35 folded and stitched for application to the body sheet of the fabric to form the pockets thereon.

Fig. 3 is an enlarged, fragmentary sectional perspective taken through the fabric 40 on the plane indicated by line 3—3 of Fig. 1.

Referring to the drawing, the body of the fabric is composed of flexible material, and, in the present instance, comprises a body sheet 10 of any standard width to which are 45 stitched strips 11. The strips 11 are relatively narrow and long and are formed with transversely extending tucks 12 at preferably equi-distantly spaced-apart points throughout the length of the strip. The 50 tucks 12 are secured in the strip by lines of stitching 13 and form partitions dividing

the tucked side of the strip into a plurality of compartments or pockets. The tucks 12 are relatively deep and are stitched at their free edges by lines of stitching 14 to one 55 face of the body sheet 10. The upper side of the tuck constitutes one edge portion of the adjacent pocket, while the lower side of the tuck constitutes the underlying edge portion of the adjacent pocket. As shown 60 in Fig. 3, the pockets or compartments are arranged in slightly overlapping relation to form a flexible body portion of uniform thickness throughout its extent. The longitudinal edges of the strips 11 are preferably overlapped and secured together by lines of stitching 15 to secure the strips to the body sheet 10 and close the ends of the 65 pockets of the several rows.

The pockets or compartments thus formed 70 are filled with infusorial earth, or other like substance, to render the fabric thus constructed impervious to temperature changes, vibration, and the like, and to impart a body and thickness to the fabric. In filling 75 the pockets, the strip 11 at one edge portion of the sheet 10 is first filled, the second strip 11 is then placed with its longitudinal edge in underlapping relation with respect to the free edge of the first strip, and the overlapping edges of the adjacent strips are secured to the sheet 10 by the line of stitching 15. The pockets in the second strip are now 80 filled and the third strip is applied to the sheet 10 in the above described manner for 85 closing the second row of pockets and closing the inner ends of the third row of pockets. Fabric thus constructed contains a plurality of adjacent pockets which overlap at their lateral edges and which lie close 90 together at their opposite ends.

The fabric is adapted to be used in making up helmets and articles of clothing particularly for aviators and soldiers to protect them from sound vibration and from climatic conditions. The material may also be used in the manufacture of blankets, automobile hood covers, and in all other articles where heat and vibration insulation is required.

100 What is claimed is—

In a heat insulating material, the com-

bination, of a body sheet, strips secured at opposite ends to the body sheet and having their adjacent longitudinal edges overlapping and stitched to the body sheet, said strips having transverse tucks spaced apart throughout the lengths of the strips and secured at their free edge portions laterally against the body sheet beneath the strips to form overlapping, independent pockets be-

tween the strips and the sheet, and a filler 10 of infusorial earth packed in said pockets.

In testimony whereof I affix my signature in presence of two witnesses.

FRANK A. GILCREST.
